DESIGN FOR A MONEY CLIP

Charles E. Mills, Cleveland, Ohio, assignor to Juno Products Company, an Ohio partnership composed of Erick Weinberger and S. Weinberger

Application June 7, 1946, Serial No. 130,503

Term of patent 3½ years

(Cl. D74—2)

To all whom it may concern:

Be it known that I, Charles E. Mills, a citizen of the United States, residing in Cleveland, in the county of Cuyahoga, State of Ohio, have invented a new, original, and ornamental Design for a Money Clip, of which the following is a specification, reference being had to the accompanying drawing, forming a part thereof.

Fig. 1 is a front elevational view of a money clip showing my new design, the head of a human being shown thereon being conventional and not intended for any particular person; and Fig. 2 is a side view thereof.

I claim:

The ornamental design for a money clip, substantially as shown and described.

CHAS. E. MILLS.
